INCANDESCENT CATHODE DISCHARGE TUBE

Application filed May 28, 1927, Serial No. 194,924, and in the Netherlands June 8, 1926.

The present invention relates to incandescent cathode discharge tubes and has for its object a particular cathode arrangement which may be advantageous in certain cases.

With certain types of cathodes or in particular those required to yield a definite emission at a given potential and strength of current, the wire is so long sometimes that if it is stretched out to its full length it cannot be introduced across the neck of the bulb. If on the other hand the wire is bent over in a V-shaped or hairpin-shaped manner, the effective length of the cathode is too short as in that case at each point of attachment or support a length of 4 to 5 millemetres is lost for the emission because the heat is conducted away and only two short pieces in the middle are heated enough to emit electrons.

According to the invention, the cathode is constructed of two or more pieces of unequal length connected in series. The longer piece only takes an active part in the emission, whereas the shorter piece, or pieces as the case may be, practically do not emit because the heat is conducted away along the leads and supporting wires.

In this case the latter non-emitting portions are preferably arranged outside the space enclosed by the anode and the grid so that only the effective portion of the cathode lies in this space and thereby a favorable influence is exercised on the characteristics of the tube.

A single example may serve for illustration:

A tungsten cathode coated with barium oxide must have a length of about 30 millemetres for a current of 0.08 ampere, at a tension of 2 volts to heat the wire to incandescence. Now the greatest wire length which can be introduced in a stretched state through the normal bulb neck of a receiving valve is some 24 millemetres. If the 30 millemetres wire is bent into a U or V shape and supported at the ends and in the middle, the length of the two emitting portions or the effective length of wire is $2 \times (15 - 2 \times 5) = 10$ millemetres because at each point of support 5 millemetres remain inactive by cooling:

This length will hereinafter be referred to as "useful length".

If, according to the invention, one end of the wire is bent over for a length of 6 millemetres or, which is better, if the two ends are bent over for a length of 3 millemetres, so that the longer portion will have a length of 24 millemetres (the allowable length which can be introduced thru the bulb neck) the useful length is then $24 - 2 \times 5 = 14$ millemetres.

In the latter case the useful length is consequently 40% greater than in the first case so that the inclined portion of the characteristic curve of the tube resulting from plotting plate current against grid potential will be materially greater.

The ends of the wire may be bent over at right angles but with a flat construction of anode and grid it is more advantageous to bend the said ends so as to produce a Z.

It is preferable that the non-emitting part of the cathode should be equally distributed at the two ends so that it would be immaterial how the polarity of the cathode terminals is chosen. If the non-emitting part is not equally distributed at the ends, then the potential difference between grid and cathode is dependent upon which end the grid connection is made.

If the incandescent body consists of two parallel wires, it is possible for each of these wires to have one end bent over at right angles and the two parts can be joined so as to form an oblong rectangle in which the leads engage two oppositely disposed vertexes, or a single wire could be bent around four supporting members so as to form a closed rectangle with two of the supports serving as leads as in the former case.

The accompanying drawings show some embodiments of the invention. In the said drawings:

Figure 1 shows a stem supporting a single incandescent wire, one end of which takes no part in the emission.

Figure 2 shows a stem with a flat arrangement of anode and grid and with a symmetrical construction of the single incandescent wire.

Figure 3 shows a stem with two parallel incandescent wires joined by two inactive portions of wire forming a rectangle.

Referring to Fig. 1 the cathode consists of two portions 1 and 2, of which the greater portion 1 is arranged within the space enclosed by the anode 7 and the grid 6, at least in so far as the emitting part of the wire is concerned. As pointed out above, the heat is conducted away along the leads 3 and 5 and along the supporting wire 4 which carries the vertex of the cathode so that the temperature of the wire ends placed outside the just mentioned space is not sufficiently raised to impart to these ends an electronic emission of any importance.

In this unsymmetrical construction, the potential drop occurring in the portion 2 results in a material variation in the potential difference between the grid and cathode depending upon whether the grid 6 (if desired with the interposition of a biasing battery) is connected with the lead 5 or with the lead 3.

For this reason the constructions shown in Figures 2 and 3, in which there is symmetry, are to be preferred.

In the construction according to Figure 2 the incandescent wire consists of a long central piece 1 and two smaller pieces 2 and 12 of equal lengths which are sharply bent over so as to produce a Z. The portion 1 passes diagonally through the flat substantially rectangular space enclosed by the anode 7 and the grid 6. The current is supplied along the leads 3 and 5 and the ends of the diagonal portion are supported by carriers 4 and 14 respectively. The portion 1 is the longest straight length that can be slid through the bulb-neck.

Figure 3 shows two wires similar to Figure 1 which are connected in parallel and which are united to form a rectangle. The current is supplied along the leads 3 and 5, and the two other vertexes are supported by carriers 4 and 14. The anode 7 and the grid 6 are the same construction as shown in Figure 2.

What I claim is:

1. A cathode for a discharge tube having the form of a rectangle, the portions of said cathode forming the longer sides of the rectangle being electron emitting portions, the shorter sides being resistances only, and leads to said cathode attached to diagonally opposite corners of the rectangle.

2. In a discharge tube, a cathode consisting of a pair of filaments connected in parallel, said filaments being in the form of a rectangle, a press having leads passing therethru connected to the ends of the filaments, and supports sealed in the press connected to points of the filament intermediate of the leads, said supports engaging diagonally opposite corners of the filamentary rectangle.

3. In an electron discharge tube having an anode, at least one grid and a cathode, said cathode having the form of an oblong rectangle comprising a plurality of emitting portions in parallel, said cathode portions each having non-emitting portions associated therewith serving as resistances only, the two narrow sides of said rectangle being arranged outside the space enclosed by the anode and the grid and leads engaging two oppositely disposed vertexes of said rectangle.

4. A cathode for a discharge tube having the form of a four-sided geometric figure, only one pair of opposite portions of said cathode being electron emitting, the other pair of opposite portions being resistances only, and leads attached to diagonally opposite corners of said four-sided cathode.
